(No Model.)

R. S. MITCHELL.

PITMAN.

No. 358,364.

Patented Feb. 22, 1887.

UNITED STATES PATENT OFFICE.

RUFUS S. MITCHELL, OF BEARDSTOWN, ILLINOIS.

PITMAN.

SPECIFICATION forming part of Letters Patent No. 358,364, dated February 22, 1887.

Application filed May 7, 1886. Serial No. 201,456. (No model.)

To all whom it may concern:

Be it known that I, RUFUS S. MITCHELL, of Beardstown, in the county of Cass and State of Illinois, have invented certain new and useful 5 Improvements in Pitmen; and I do hereby declare that the following is a full, clear, and exact description thereof, reference being had to the accompanying drawings, and to the letters of reference marked thereon, which form part 10 of this specification, in which—

Figure 1 is an elevation of a pitman embodying my invention. Fig. 2 is a vertical section of the same. Fig. 3 is a plan view. Figs. 4, 5, and 6 are detail views of the same. Fig. 15 7 is a front and edge view of a modification. Fig. 8 represents a similar view of another modification of the pitman.

This invention relates to improvements in pitman-rods for sewing-machines and other 20 light machinery; and it consists in the novel construction and arrangement of parts of the pitman, whereby wear upon the journals of the same, or upon the crank-pins to which the pitman is attached, may be compensated and 25 the pitman always kept in smooth and easy working condition, as will be fully understood from the following description, when taken in connection with the accompanying drawings, and particularly specified in the claims.

30 A designates the pitman, of suitable size, and having central longitudinal cuts or narrow slots, *a'*, extending from its journals inward; or the pitman may be made in two equal sections, suitably united, the joints between 35 the sections answering the purpose of the slot, the object of the slots *a'* being to admit of lateral adjustment of the journals, as will be hereinafter described. The outer ends of the pitman are slotted, as shown at *a*, the slots being just the width of the diameters of the journals. The inner half of the journal is formed 40 in the pitman, and the outer half on the inner end of a block or traveler, B, which is adapted to enter and fit snugly while moving 45 freely within the slot *a*, as shown. The outer ends of the pitman-rod and the block B are made cylindrical, as shown, and are slightly tapered outward, for a purpose hereinafter explained.

50 C designates metal bands or rings which fit

snugly over the outer ends of the pitman and blocks B, and are secured in place by means of bolts or pins *c*, which pass through proper diametric openings in the rings and through the ends of the pitman and blocks B. The 55 blocks B are slotted where pins *c* pass through them, so as to permit the blocks free longitudinal movement within the slots *a*, while preventing their escape therefrom.

D designates rings or bands placed loosely 60 upon the ends of the pitman and blocks B, to the inner side of rings C, by which they are kept in place. The adjacent edges of rings C and D are provided with a similar number of cam-faces, which act together to spread apart 65 the rings.

The inner smooth edges of rings D engage against pins or studs *b*, secured on opposite edges of blocks B, so that when the rings D are turned until their cams engage against the 70 cams on rings C the blocks B are forced inward against the arm or crank-pin secured within the journal.

The rings D may be provided with a milled outer surface to secure a better grasp for the 75 fingers or hand when tightening the same against the rings C.

It is obvious from the foregoing description that any longitudinal wear on the journals of the pitman or wear on the crank-pins secured 80 within the same can be easily compensated by tightening the rings D, as described; and by having the ends of the pitman and blocks conical the rings D, when forced inward by engagement of their cams against those of rings 85 C, will take up lateral wear of the journals or crank-pins, the slots *a'* or joints between the sections of pitman admitting this lateral adjustment, both lateral and longitudinal compensation being effected by one turn of either 90 ring D.

In Fig. 7 I have shown a modification of the adjusting-rings, in this case only one ring being used. The ends of the pitman and blocks B are made as before described; but instead of 95 bands C a band, E, having cam-slots *e* is used, the pins *c* passing through these slots and affording bearings for their cams to act against to effect the desired compensation. Fig. 8 shows another modification, all the parts 100

being made as described, except the bands C. In this case only one band is used, having its outer edge provided with two cams engaging against the securing pin c, and its inner edge engaging against the studs of the block B, as shown. These modifications may be found useful in some instances; but the first-described construction I deem preferable, as affording greater stability, strength, and a 10 nicer adjustment.

Having described my invention, I claim—

1. A pitman-rod provided with a rounded outer end slotted longitudinally from its bearing outward, in combination with a block fitting and moving within the slot, and a cam-faced ring or rings adapted to cause the blocks to compensate wear of the journal-pin in the bearing, substantially as specified.
2. The combination, with a pitman-rod provided with rounded and slotted ends outside of its journals, and having blocks fitted and moving within the slots, of cam-faced rings fitting upon the ends of the pitman and adapted to cause the blocks to compensate wear of the journals, by means substantially as described.
3. The combination, with a pitman-rod having its ends outside of its journal rounded and slotted and provided with blocks fitting within

the slots, as described, of the rings C, secured on the ends of the pitman and blocks and provided with cam-faces on their inner edges, and rings D, placed upon the ends of the pitman and blocks at the inner side of rings C, and provided with cam-faces engaging those of the latter, whereby any wear of the journals or 35 crank-pins within the same can be compensated, all substantially as specified.

4. The combination, with a pitman-rod having its ends outside of its journal made conical and slotted, and having blocks B playing 40 within the slots, as described, of rings C, secured upon the ends of the pitman, provided with cam-faces on their inner edges, and rings D, placed upon the ends of the pitman to the inner sides of rings C, and having cam-faces 45 adapted to engage those of the latter, and a smooth inner edge impinging against stop-lugs on the block B, all substantially as and for the purpose described.

In testimony that I claim the foregoing as 50 my own I affix my signature in presence of two witnesses.

RUFUS S. MITCHELL.
